UNITED STATES PATENT OFFICE

ALBERT E. R. SPEIDEL, OF EDGEWOOD, RHODE ISLAND

DESIGN FOR AN END HOOK

Application filed July 28, 1930. Serial No. 36,490. Term of patent 3½ years.

To all whom it may concern:

Be it known that I, ALBERT E. R. SPEIDEL, a citizens of the United States of America, residing at Edgewood, county of Providence, State of Rhode Island, have invented a new, original, and ornamental Design for an End Hook, of which the following is a specification, reference being had to the accompanying drawing, forming a part thereof.

Fig. 1 is a top plan view; and Fig. 2 is a side elevation of an end hook, showing my new design.

I claim:

The ornamental design for an end hook, substantially as shown.

ALBERT E. R. SPEIDEL.
